R. D. HUNNEMAN

ART OF DISTILLING HYDROCARBON OILS

Filed Dec. 12, 1924

Inven^{tor}:
Roger D. Hunneman
By ^{his} daughter, Lee, ^{and} son, Clinton & Miles,
Atteys.

UNITED STATES PATENT OFFICE.

ROGER D. HUNNEMAN, OF CHICAGO, ILLINOIS, ASSIGNOR TO STANDARD OIL COMPANY, OF WHITING, INDIANA, A CORPORATION OF INDIANA.

ART OF DISTILLING HYDROCARBON OILS.

Application filed December 12, 1924. Serial No. 755,429.

The present invention relates to improvements in the distillation of hydrocarbon oils, and more particularly of lubricating oils or distillates, for the removal of their lighter fractions and the formation of heavier, viscous lubricant residues. It will be fully understood from the following description, illustrated by the accompanying drawing; in which the figure shows diagrammatically, 10 and partly in section, apparatus suitable for carrying the invention into effect.

Referring more particularly to the drawing, the numeral 5 indicates a furnace setting, in which is provided a heating coil 6, 15 of which the initial portion 6^a may suitably be of a pipe of a smaller cross-sectional area than the subsequent portion 6^b. Oil is supplied to the coil 6 through valved pipe 7. From the coil 6 a pipe 8 leads into an enlarged chamber 9 which may be formed at an intermediate point in a stripping and rectifying tower 10, which may be lagged, if desired.

A number of spaced stripping plates 12 (shown diagrammatically as of the bubble type) are provided in the tower 10 below the enlarged chamber 9, and a number of fractionating plates 13 are provided in the tower above the enlarged chamber 9. The 30 fractionating plates are preferably of a type providing a low pressure drop; for example, of the disc and doughnut type; or a filled tower may be used. A heat exchange coil 28 may be provided in the upper portion of the tower, if desired. A pipe 14 leads into the base of the tower, terminating in a suitable perforated distributing device 15, the perforations being preferably downwardly directed. Steam or other inert gas may be 35 supplied within the tower by this means.

Vapors pass out of the tower through the pipe 16 to the condenser 17, at a suitable point in which a trap 18 may be interposed for the separation of condensed oil and uncondensed steam or other uncondensed vapor. Condensed liquid continues through the remainder of the condenser 17 (which acts as a cooler therefor) and is conducted by valved pipe 19 to receiver 20, to the vapor space 50 of which the suction line 21 of a vacuum pump 22 is connected. Liquid is discharged from receiver 20 through valved line 23.

Uncondensed vapor and/or steam may be drawn from the trap 18 through line 24 by pump 25, and forced by it through line 26

to a suitable intermediate point in the coil 6.

In carrying out the invention the hydrocarbon oil to be distilled is forced through line 7 by any suitable supply means, as a pump, (not shown) into and through the coil 6, in which it is heated to the temperature necessary to produce the desired character of overhead or residue product. Steam or other vapor may be supplied to the coil 6 at an intermediate point through the line 26, as hereinafter set forth.

From coil 6 the heated oil passes through line 8 into the enlarged chamber 9, in which a separation of vapors and unvaporized liquid takes place. The liquid descends in the column 10 through the stripping plates 12, in counter-current to steam or other inert vapor, admitted into the column at or near its base through supply pipe 14 and distributor 15. The liberated vapors, together with the steam and vapors from the stripping plates 12, rise through the fractionating plates 13, condensate refluxing to the lower portion of the column, or being removed from any suitable point above the chamber 9 by any suitable standard means. Any desired additional or controlled cooling of the vapor, before issuing from the column, may be effected by passing a suitable cooling medium through the heat exchange coil 28. The cooling medium may suitably be the stock to be distilled, which may pass from coil 28 through pipe 29 to the conduit 7 leading to the coil 6. Vapors and steam pass through vapor line 16 to condenser 17, there they may be condensed and cooled.

If desired, a trap 18 may be inserted at an intermediate point in the condenser, at which the steam is still uncondensed. Steam and accompanying uncondensed vapors may be withdrawn at the trap, the liquid condensate continuing through the coil to the receiver 20. The uncondensed steam and vapors from the trap 18 may be drawn through pipe 24 by the pump 25 and forced through pipe 26 into the coil 6, preferably at an intermediate point therein. If desired, the steam so fed in may be preheated by any suitable means, as by a tar heat exchanger, as is well recognized in the art. Steam from another source may be admitted through the line 27.

If desired, a vacuum may be maintained on the tower and heating system by means of the pump 22, an absolute pressure to 10 to 110

50 millimeters being desirably maintained where the oil enters the tower.

The process is particularly adapted for the production of residue stocks, such as viscous lubricating oils, from reduced crude oils or from distillates. Thus, it may be employed for the manufacture of cylinder stocks or of distillate or residue stocks. In operating for the production of viscous lubricating stocks as residues from paraffin distillates, it has been found desirable to control the heating of the coil 6 to bring the oil to a temperature of 625 to 700° F. The steam employed may vary from 1 to 6 10 pounds per gallon of oil distillate, about one-third to one-half of this being admitted into the coil and the remainder into the tower. The proportion of steam and vapor withdrawn at the trap and returned to the 15 coil may obviously be readily controlled.

The temperatures and amounts of steam employed are controlled in accordance with the characteristics of products desired. The bottom stocks obtained are of unusually high 20 viscosity as compared with bottom stocks obtained in ordinary continuous operations. Thus, a certain paraffin distillate, distilled in the ordinary way to a 20% bottom, gives a product having a viscosity of about 3400 25 sec. Saybolt at 100° F.; the same oil, distilled by the present method under a vacuum of 28.8 mercury gives a 20% bottom having a viscosity of over 15000 sec. Saybolt at 100° F. At the same time, the overhead under 30 the present method of operation was of higher viscosity than that obtained by prior methods.

The cooling coil 28 in the upper part of the fractionating end of the column may be 40 entirely omitted, if desired, and particularly when a sharp removal of heavy ends from the overhead product is not material. With a suitable cooling means, such as the coil 28, in the top of the column, the temperature of 45 the issuing vapors and the amount of reflux may be readily controlled in accordance with the character of products desired.

The process may be used with other types of oils; for example, for the removal of 50 lighter fractions from crude and reduced crude oils.

I claim:

1. The method of distilling hydrocarbon oils comprising passing the oil in a confined stream of restricted cross section through a heating zone into an enlarged separating chamber, separately removing from said separating chamber vapors and unvaporized liquid, passing the unvaporized 55 liquid in countercurrent to a current of steam, and forcing at least a part of said steam and vapors carried thereby into the stream of oil flowing through the heated zone.

2. The method of distilling hydrocarbon

oils which comprises passing such oil in a confined stream of restricted cross-section through a heating zone, forcing steam into the stream of heated oil at an intermediate point in its passage through the heating 70 zone and after it has traversed a substantial portion thereof, discharging the stream of oil into an enlarged chamber, wherein separation of vaporized and unvaporized products takes place, removing unvaporized oil 75 therefrom and immediately subjecting said unvaporized oil to direct contact with steam, thereby removing lighter constituents from the oil.

3. The method of distilling hydrocarbon 80 oils which comprises passing such oil in a confined stream through a heating zone, forcing steam and vapors into the stream of heated oil at an intermediate point before it leaves the heating zone, discharging 85 the stream of oil into an enlarged chamber, wherein separation of vaporized and unvaporized products takes place, removing unvaporized oil therefrom, immediately subjecting said unvaporized oil to direct contact with steam, thereby removing lighter 90 constituents from the oil, and forcing part of the steam and vapors thus removed into the stream of oil in the heating zone.

4. The method of distilling hydrocarbon 95 oils comprising passing the oil in a confined stream through a heating zone, discharging the oil into a separating chamber, separately removing from said separating chamber vaporized products and unvaporized oil, 100 passing the unvaporized oil in countercurrent to a current of steam, forcing part of the steam and vapors carried thereby into the stream of oil in the heating zone, and maintaining sub-atmospheric pressure on the 105 separating chamber.

5. The method of distilling hydrocarbon oils comprising passing the oil in a confined stream through a heating zone, discharging the oil into a separating chamber, passing the 110 unvaporized oil in countercurrent to a current of steam, subsequently subjecting said steam with the vapors from the separating chamber to refluxing action, and maintaining sub-atmospheric pressure on the system.

6. The method of distilling hydrocarbon oils which comprises passing the oil in an externally heated confined stream through a heating zone, discharging the oil into an unheated separating chamber, supplying steam 120 in said chamber so as to pass through the liquid therein, removing separated vapors and steam from said chamber, and subjecting the removed vapors and steam to a controlled refluxing action.

7. The method of distilling hydrocarbon oils which comprises passing the oil in an externally heated confined stream through a heating zone, discharging the oil into an unheated separating chamber, supplying steam 125

in said chamber so as to pass through the liquid therein, removing separated vapors and steam from said chamber, subjecting the removed vapors and steam to a controlled refluxing action and returning reflux to the separating chamber.

8. The method of distilling hydrocarbon oils comprising passing the oil in a confined stream through a heating zone, discharging the oil into a separating chamber, passing the unvaporized oil countercurrent to a current of steam, subsequently subjecting said steam to refluxing action with the vapors from the separating chamber, partially cooling the refluxed vapors and steam, separating uncondensed steam from condensate therefrom and introducing said steam into the confined stream of oil in the heating zone.

9. The method of distilling hydrocarbon oils comprising passing the oil in a confined stream through a heating zone, discharging the oil into a separating chamber, passing the unvaporized oil countercurrent to a current of steam, subsequently subjecting said steam with the vapors from the separating chamber to refluxing action, partially cooling the refluxed vapors and steam, separating uncondensed steam from condensate therefrom, introducing said steam into the confined stream of oil in the heating zone at an intermediate point, and maintaining sub-atmospheric pressure on the system.

10. In distillation apparatus, a tower having an intermediate enlarged chamber, stripping plates therebelow, refluxing plates above said chamber, means for introducing steam into the lower portion of said tower, a heating coil emptying into the enlarged chamber in the tower, means for supplying oil to the heating coils, and means for maintaining sub-atmospheric pressure within the tower.

11. In distillation apparatus, a tower having an intermediate enlarged chamber, stripping plates below the chamber, refluxing plates above the chamber, means for heating a continuously flowing stream of oil, means for discharging it into the tower within the enlarged chamber, a vapor outlet from the tower, a condenser connected to said outlet, a

trap at an intermediate point in the condenser for separating liquids from uncondensed vapors, and means for introducing uncondensed vapors separated at the trap into the flowing stream of oil.

12. In distillation apparatus, a tower having an intermediate enlarged chamber, stripping plates below the chamber, refluxing plates above the chamber, means for heating a continuously flowing stream of oil, means for discharging it into the tower within the enlarged chamber, means for partially condensing vapors issuing from the tower, and means for introducing uncondensed vapors into the flowing stream of oil.

13. The method of distilling hydrocarbon oils which comprises passing the oil in a confined stream through a heating zone, discharging the oil into a separating chamber, supplying steam in said chamber at substantially the same temperature as the oil and in thermal equilibrium therewith, separately removing unvaporized oil and vapors from said chamber, subjecting the removed unvaporized oil to the action of live steam, thereby removing lighter fractions therefrom, withdrawing from the system the thus treated unvaporized oil, and subjecting the removed lighter fractions with the vapors from the separating chamber to a controlled refluxing action.

14. The method of distilling hydrocarbon oils which comprises passing the oil in a confined stream through a heating zone, discharging the oil into a separating chamber, supplying steam in said chamber at substantially the same temperature as the oil and in thermal equilibrium therewith, separately removing unvaporized oil and vapors from said chamber, subjecting the removed unvaporized oil to the action of live steam, thereby removing lighter fractions therefrom, withdrawing from the system the thus treated unvaporized oil, commingling the removed lighter fractions with the vapor contents of the separating chamber, and subjecting the vapors removed from the separating chamber to a controlled refluxing action.

ROGER D. HUNNEMAN.

DISCLAIMER

1,676,609.—*Roger D. Hunneman, Chicago, Ill.* ART OF DISTILLING HYDROCARBON OILS. Patent dated July 10, 1928. Disclaimer filed May 8, 1931, by the assignee, *Standard Oil Company*.

Hereby enters this disclaimer to claims 5, 6, and 7 of said patent, which claims are in the following words, to-wit:

“5. The method of distilling hydrocarbon oils comprising passing the oil in a confined stream through a heating zone, discharging the oil into a separating chamber, passing the unvaporized oil in countercurrent to a current of steam, subsequently subjecting said steam with the vapors from the separating chamber to refluxing action, and maintaining sub-atmospheric pressure on the system.

“6. The method of distilling hydrocarbon oils which comprises passing the oil in an externally heated confined stream through a heating zone, discharging the oil into an unheated separating chamber, supplying steam in said chamber so as to pass through the liquid therein, removing separated vapors and steam from said chamber, and subjecting the removed vapors and steam to a controlled refluxing action.

“7. The method of distilling hydrocarbon oils which comprises passing the oil in an externally heated confined stream through a heating zone, discharging the oil into an unheated separating chamber, supplying steam in said chamber so as to pass through the liquid therein, removing separated vapors and steam from said chamber, subjecting the removed vapors and steam to a controlled refluxing action and returning reflux to the separating chamber.”
